UNITED STATES PATENT OFFICE

2,614,535

CLEANSING DEVICE FOR ROCK DRILLS

William A. Morrison, Easton, Pa., assignor to Ingersoll-Rand Company, New York, N. Y., a corporation of New Jersey

Application October 4, 1947, Serial No. 778,013

6 Claims. (Cl. 121—10)

1

This invention relates to rock drills, and more particularly to a cleansing device for fluid actuated rock drills of the reciprocating piston type.

One object of the invention is to minimize the amount of pressure fluid required for actuating the rock drill and cleansing the hole being drilled.

Another object is to utilize all the pressure fluid exhausted from the cylinder of the rock drill for ejecting the cuttings from the hole being drilled.

Other objects are to obviate the objectionable noises usually occasioned by the exhaust fluid discharging directly from the rock drill to the atmosphere and the spraying of such oil into the atmosphere as may be entrained in the exhaust fluid.

Another object is to permit a prolonged and uninterrupted flow of pressure fluid under full line pressure through the rock drill and the working implement for blowing the cuttings from the drill hole and to hold the distributing valve and the piston immovable during the blowing period.

Other objects will be in part obvious and in part pointed out hereinafter.

In the drawings accompanying this specification and in which similar reference numerals refer to similar parts,

Figure 1 is a side elevation, partly broken away, of a rock drill embodying the invention, and

Figure 2 is an elevation, partly in section, showing an enlarged view of the rearward portion of the rock drill.

Referring more particularly to the drawings, 20 designates, in general, the rock drill and 21 its cylinder having a piston chamber 22 and a piston 23 reciprocable therein. At the front end of the cylinder is a front head 24 having a skirt portion 25 to serve as a closure for the end of the piston chamber 22, and at the rearward end of the cylinder 21 is an enlarged bore 26 containing a closure 27 for the adjacent end of the piston chamber.

The closure 27 is suitably recessed to accommodate rotation mechanism, for the piston 23, comprising a ratchet ring 28 that lies within the closure and may be secured fixedly thereto in any suitable manner, and within the ratchet ring is the head 29 of a rifle bar 30 that extends axially of the piston chamber and into an elongated cavity 31 in the piston 23. The head 29 carries the usual spring-pressed pawls 32 for engagement with the teeth 33 of the ratchet ring, and the flutes 34 on the rifle bar are slidably interlocked with ribs 35 within a nut 36 threaded into the rearward end of the piston 23. The rotation

2

mechanism is of a conventional type and operates in a well known manner to cause a partial rotary movement of the piston during its rearward stroke and to release the rifle bar from the ratchet ring during the working stroke of the piston.

The closure 27 is retained in assembled position by a sleeve 37 extending into the outer portion of the cavity 31 and containing a block 38 that seats against the ratchet ring 28 and overlies the head 29 to serve as an abutment therefor. The sleeve 37 and the block 38 are pressed against the closure and the ratchet ring by a spring 39 seating at one end against the sleeve and at its other end against a plate 40 mounted on the side rods 41 that secure the front head 24 to the cylinder 21.

The piston 23 is of the differential type having a forward reduced pressure surface 42 and a relatively large rear pressure surface 43. The front pressure surface 42 is constantly exposed to pressure fluid conveyed thereto by an inlet passage 44 leading from a valve chamber 45, and pressure fluid is intermittently admitted into the rearward end of the piston chamber 22 through an inlet port 46 controlled by a valve 47 reciprocable in the valve chamber 45. The valve chamber is defined by a bushing 48 and its front end is in constant communication with the inlet passage 44.

Pressure fluid passes to the passage 44 through a passage 49 extending throughout the length of the valve 47 and radial ports 50 in the intermediate portion of the valve which open into an annular groove 51 that is in constant communication with a supply conduit 52 threadedly connected to the casing 21. The annular groove 51 is so located that in the foremost limiting position of the valve 47 it will be in communication with the inlet passage 46 for charging the rear end of the piston chamber 22 and will be blanked-off by the wall of the valve chamber 45 to cut-off the flow of pressure fluid to the inlet passage 46 in the other limiting position of the valve.

The front and rear ends of the valve are constantly subjected to pressure fluid and constitute, respectively, actuating surfaces 53 and 54. The actuating surface 53 is of somewhat larger area than the actuating surface 54 so that, in the absence of other forces acting against the valve for altering its position, the valve will normally be actuated rearwardly and held thus by the pressure fluid acting against the surface 53. In order, therefore, to throw the valve forwardly for charging the rearward end of the piston chamber, said valve is provided with an additional actuating

surface 55 that is intermittently subjected to pressure fluid to augment the force of the pressure fluid acting against the actuating surface 54.

The pressure fluid serving this function is conveyed from the front end of the piston chamber by a kicker passage 56 which is controlled by the piston 23, and the exhaust of such fluid is also controlled by the piston and is effected through a branch 51 of the kicker passage 56 opening into the piston chamber rearwardly of the front end of the kicker passage and through an annular groove 58 in the piston and an atmospheric exhaust port 59 in the wall of the cylinder 21.

In order to economize in the amount of pressure fluid required for operating the rock drill and for cleansing the drill hole, all of the pressure fluid serving to drive the piston 23 on its working stroke is discharged into the drill hole. This has the added advantages of muffing the exhaust noises and of preventing the spraying into the atmosphere of such oil as is usually entrained in the pressure fluid for lubricating the movable parts of the rock drill. To these ends the nut 36 is provided with a series of passages 60 that extend lengthwise thereof and afford communication between the rearward end of the piston chamber 22 and the cavity 31, and in the forward or stem portion 61 of the piston is a passage 62 to communicate the cavity 31 with a channel 63 within a drilling implement 64 secured to the front end of the stem 61 by a clamp 65. The drilling implement 64 is shown as consisting of a tubular member 66 having threadedly attached thereto a drill bit 67 having a passage 68 which communicates with the channel 63 and directs the exhaust fluid toward the bottom of the drill hole 69.

The flow of exhaust fluid through the piston and the drilling implement is controlled by a valve 70 supported, in the present instance, by the rifle bar 30. The valve 70 is preferably in the form of a sleeve which may be split, if desired, and encircles an end of a stem 71 abutting the lower end of the rifle bar 30. The stem 71 is clamped against the rifle bar by a bolt 72 which extends through the two and has a head 73 overlying the end of the valve 70 to retain it on the stem 71. The valve 70 is of slightly smaller diameter than the passage 62 so that it may enter readily thereto to cooperate with the surface of the passage for controlling the flow of fluid therethrough accordingly as the piston reciprocates and is so positioned that when the piston approaches the end of its working stroke the passage 62 will move out of the transverse plane of the valve to place it in communication with the rearward end of the piston chamber shortly before the piston reaches the end of its working stroke.

To the end that an uninterrupted flow of pressure fluid may be introduced into the drill hole directly from supply whenever the intermittent charges of exhaust fluid thereto are found to be insufficient to prevent the accumulation of cuttings around the drill bit, the rock drill is provided with means for holding the valve 47 selectively stationary in its foremost limiting position to place and maintain the rearward end of the piston chamber 22 in communication with the supply conduit 52. The means serving this function comprises a plunger 74 slidable within a chamber 75 in a head 76 forming a closure for the rearward end of the valve chamber 45.

The chamber 75 has a reduced portion 77 which accommodates both the plunger and a stem

portion 19 of the valve and has a rearward enlarged portion 78 that accommodates a head 79 of the plunger having a rearward pressure surface 80 which is subjected selectively to pressure fluid to press the plunger against the valve and hold the valve in position to communicate the rearward end of the piston chamber with the supply conduit 52. The end of the plunger confronting the valve 45 also constitutes a pressure surface 81 which is subjected to the pressure fluid within the passage 49 for normally holding the plunger out of engagement with the valve.

A closure is provided for the chamber 75 in the form of a plate 82 which, together with the head 76, is clamped to the rock drill by bolts 83. The pressure fluid employed for pressing the plunger against the valve is conveyed to the enlarged portion 78 of the chamber 75 by a conduit 84 having a manually operable valve 85 that also serves to exhaust the pressure fluid from the chamber 75 to the atmosphere.

The operation of the device is as follows: With the piston 23 and the valve 47 in the foremost limiting positions, as shown in Figure 2 of the drawings, pressure fluid entering the passage 49 from the supply conduit 52 and acting against the actuating surface 53 will move the valve rearwardly and cut-off the flow of pressure fluid into the rearward end of the piston chamber. At the same time pressure fluid will leak from the passage 44 to the front end of the piston chamber through the natural clearance existing between the peripheral surface of the piston and the wall of the piston chamber and, acting against the actuating surface 42, will lift the piston. As the piston proceeds upwardly it next uncovers the kicker passage 56 and pressure fluid will flow into the valve chamber against the actuating surface 55 and again shift the valve 47 forwardly.

Pressure fluid will then flow through the inlet passage 46 into the rearward end of the piston chamber and drive the piston 23 forwardly on its working stroke. When, during this movement of the piston, the portion thereof defining the passage 62 moves out of engagement with the valve 70, the fluid will escape from the rear end of the piston chamber through the piston and the drilling implement into the drill hole and blow the cuttings therefrom.

Shortly prior to the time the piston moves out of engagement with the valve 70 it uncovers the branch passage 57. The pressure fluid acting against the surface 55 of the valve 47 will then escape through the annular groove 58 and the port 59 to the atmosphere and that acting against the surface 53 will lift the valve to cut-off the admission of pressure fluid into the rear end of the piston chamber and thereby prevent the flow of fluid from supply to the drill hole without first serving to actuate the piston.

In the event that the intermittent introduction of exhaust fluid into the drill hole is found to be insufficient to maintain it free of cuttings, as is sometimes the case when drilling in soft rock, the valve 85 is manipulated to cut-off communication between the enlarged portion 78 of the chamber 75 to the atmosphere and to introduce pressure fluid into said chamber. Such pressure fluid acting against the actuating surface 80 will press the plunger against the surface 54 and thereby maintain the valve 47 in its lowermost limiting position. Pressure fluid will then flow, as an uninterrupted stream, directly from supply through the rearward end of the piston chamber 22 and through the piston and the drilling im-

plement into the drill hole to effect a thorough cleansing thereof. After the drill hole has been freed of rock cuttings the valve 85 is restored to its former position to release the valve 47.

As will be readily appreciated from the foregoing description, by exhausting the fluid serving to actuate the piston from only one end of the piston chamber and utilizing such fluid for cleansing the drill hole the pressure fluid required for both functions may be held to a minimum, the oil entrained in the pressure fluid for lubricating the movable parts of the rock drill will be discharged into the drill hole instead of directly into the atmosphere and the exhaust noises will be entirely eliminated.

I claim:

1. In a fluid actuated rock drill, the combination of a casing having a piston chamber, a piston reciprocable in the piston chamber, a passage in the casing for constantly conveying pressure fluid from a source of supply to one end of the piston chamber for actuating the piston in one direction, a valve chamber in the casing, an inlet passage leading from the valve chamber to the other end of the piston chamber, a valve in the valve chamber controlled by the piston for intermittently valving pressure fluid through the last mentioned passage into the said other end of the piston chamber for actuating the piston in the opposite direction, a drilling implement actuated by the piston, there being passages in the piston and the drilling implement in communication with the atmosphere and constituting the sole outlet for the fluid exhausted from said other end of the piston chamber, and valve means intermittently engaging the piston for controlling the flow of exhaust fluid through the last mentioned passages.

2. In a fluid actuated rock drill, the combination of a casing having a piston chamber, a piston reciprocable in the piston chamber, a passage in the casing for constantly conveying pressure fluid from a source of supply to the front end of the piston chamber for actuating the piston rearwardly, a valve chamber in the casing, an inlet passage leading from the valve chamber to the other end of the piston chamber, a valve in the valve chamber controlled by the piston for intermittently valving pressure fluid through the second mentioned passage into the rear end of the piston chamber for actuating the piston forwardly, a drilling implement actuated by the piston, said piston and drilling implement having passages in communication with the atmosphere and the rear end of the piston chamber and constituting the sole outlet for the fluid exhausted from the rear end of the piston chamber, and a valve within the piston to cooperate intermittently with the piston for controlling the flow of exhaust fluid through the passages in the piston and the drilling implement.

3. In a fluid actuated rock drill, the combination of a casing having a piston chamber, a piston reciprocable in the piston chamber, a passage in the casing for constantly conveying pressure fluid from a source of supply to the front end of the piston chamber for actuating the piston rearwardly, a valve chamber in the casing, an inlet passage leading from the valve chamber to the other end of the piston chamber, a valve in the valve chamber controlled by the piston for intermittently valving pressure fluid through the second mentioned passage into the rear end of the piston chamber for actuating the piston forwardly, a drilling implement actuated by the

piston, said piston and drilling implement having passages in communication with the atmosphere and the rear end of the piston chamber and constituting the sole outlet for the fluid exhausted from the rear end of the piston chamber, a valve in the rock drill to intermittently extend into the passage in the piston accordingly as the piston reciprocates within the piston chamber for controlling the flow of exhaust fluid through the piston, and means for securing the last mentioned valve to the rock drill.

4. In a fluid actuated rock drill, the combination of a casing having a piston chamber, a piston reciprocable in the piston chamber, a passage in the casing for constantly conveying pressure fluid from a source of supply to the front end of the piston chamber for actuating the piston rearwardly, a valve chamber in the casing, an inlet passage leading from the valve chamber to the other end of the piston chamber, a valve in the valve chamber controlled by the piston for intermittently valving pressure fluid only to the rearward end of the piston chamber for actuating the piston forwardly, a drilling implement actuated by the piston, said piston and drilling implement having passages in communication with the atmosphere and the rear end of the piston chamber and constituting the sole outlet for the fluid exhausted from the rear end of the piston chamber, a rifle bar having spiral flutes interlocking slidably with the piston for causing rotary movement of the piston, and a valve on the rifle bar to intermittently cooperate with the surface which defines the passage in the piston accordingly as said piston reciprocates within the piston chamber for controlling the flow of exhaust fluid through the piston.

5. In a fluid actuated rock drill, the combination of a casing having a piston chamber, a piston reciprocable in the piston chamber, a passage in the casing for constantly conveying pressure fluid from a source of supply to the front end of the piston chamber for actuating the piston rearwardly, a valve chamber in the casing, an inlet passage leading from the valve chamber to the other end of the piston chamber, a valve in the valve chamber controlled by the piston for valving pressure fluid intermittently into only the rearward end of the piston chamber, a drilling implement actuated by the piston, said piston and drilling implement having passages in communication with the atmosphere and the rear end of the piston chamber and constituting the sole outlet for the fluid exhausted from the rear end of the piston chamber, a stationary valve in the rock drill cooperating with the piston to alternately open and close the passage in the piston accordingly as the piston moves away from and toward said stationary valve for controlling the flow of exhaust fluid through the last mentioned passages, and means for selectively holding the first mentioned valve immovable in the valve chamber to permit an uninterrupted flow of pressure fluid from the valve chamber through the rear end of the piston chamber and the last mentioned passages into the hole being drilled.

6. In a fluid actuated rock drill, the combination of a casing having a piston chamber, a piston reciprocable in the piston chamber, a passage for constantly conveying pressure fluid from a source of supply to the front end of the piston chamber for actuating the piston rearwardly, a valve chamber in the casing, an inlet passage leading from the valve chamber to the other end of the piston chamber, a valve in the valve chamber controlled by the piston for valving pressure

fluid intermittently into only the rearward end of the piston chamber, a drilling implement actuated by the piston, said piston and drilling implement having passages in communication with the atmosphere and the rear end of the piston chamber and constituting the sole outlet for the fluid exhausted from the rear end of the piston chamber, a stationary valve in the rock drill cooperating with the piston to alternately open and close the passage in the piston accordingly as the piston reciprocates within the piston chamber for controlling the flow of exhaust fluid through the last mentioned passages, a fluid actuated plunger for holding the first mentioned valve immovable to permit an uninterrupted flow of pressure fluid from the valve chamber through the rear end of

10

15

the piston chamber and the last mentioned passages into a hole being drilled, and means for selectively controlling the flow of pressure fluid to the plunger.
